UNITED STATES PATENT OFFICE.

GUY A. MAHANEY, OF JOKER, WEST VIRGINIA.

NECKTIE-STRETCHER.

1,254,334.

Specification of Letters Patent. Patented Jan. 22, 1918.

Application filed March 29, 1917. Serial No. 158,366.

To all whom it may concern:

Be it known that I, GUY A. MAHANEY, a citizen of the United States, residing at Joker, in the county of Calhoun and State 5 of West Virginia, have invented certain new and useful Improvements in Necktie-Stretchers; and I do hereby declare the following to be a full, clear, and exact description of the invention, such as will enable 10 others skilled in the art to which it appertains to make and use the same.

This invention relates to improvements in necktie stretchers.

The object of this invention is the provision of a necktie stretcher upon which ties may be placed and clamped thereon and held in a firm stretched position, thus removing the wrinkles and creases from the ties and prolonging the life of the ties due 20 to keeping the same in a stretched position at all times.

Another object of this invention is the provision of a pair of parallel spaced clamping members which are integrally connected 25 at one end and having a spring located between the opposing faces of their free ends and a clamping or locking ring slidably arranged on the stretching members holding a tie against the outer surface of the stretching members and the spring normally urging 30 the stretching members apart to hold the ring thereon.

A still further object of this invention is the provision of a necktie stretcher which 35 comprises a pair of substantially V-shaped members, which members are connected at one end by a loop for resiliently supporting the members in spaced relation with one another, adapted to receive a tie thereover, 40 and a locking ring embracing the members firmly clamping a tie to the outer plane surfaces, and a supporting member at the connected ends of the members for securing the device to a support.

45 A still further object of this invention is the provision of a necktie stretcher of this character, which will be simple, durable and efficient and comparatively inexpensive in construction and one that can be manufactured and sold at a small cost.

With these and other objects in view, the invention consists in the novel combination and arrangement of parts hereinafter more

fully described and set forth in the claims hereto appended. 55

In the drawing:

Figure 1 is a perspective view of my improved necktie stretcher made in accordance with this invention,

Fig. 2 is a longitudinal sectional view of 60 the same,

Fig. 3 is a transverse sectional view taken on the line 3—3 of Fig. 2.

Like numerals of reference designate corresponding parts in all the figures of the 65 drawing.

Referring more particularly to the drawing, the numeral 1 designates a necktie stretcher in its entirety which comprises a piece of flat resilient metal which is looped 70 at its medial portion as at 2 to provide the spaced stretching members 3. The stretching members have the outer plane surfaces, which are substantially V-shaped, thus providing a body of the necktie stretcher. 75

The stretching members 3 having the V-shaped plane surfaces are connected together at their apexes as at 2, thus providing the spaced diverging stretching members so that a tie when placed thereon will be 80 readily and quickly stretched and the creases removed therefrom.

Formed integrally with the inner face of one of the stretching members 3, adjacent each longitudinal side edge thereof, are the 85 guide flanges 4, which flanges terminate adjacent each end of the members 3, as at 5 and also limit the inward movement of the members 3 toward one another.

A locking ring 5' comprises the side walls 90 6 and end walls 7, said walls having their opposite edges curved outwardly and upwardly as at 8 so as to permit the ring to be freely slid upon the stretching members 3. The locking ring 5' is slipped over the 95 smaller ends or the connected ends of the stretching members and forced toward the flared ends thereof, as illustrated in Figs. 1 and 2, to firmly clasp a necktie upon the outer plane surfaces of the stretching members 3.

Formed integrally with the inner faces of the end walls 7 of the locking ring 5' are the 100 guide flanges 8', which have the horizontally directed portions 9 formed on their extreme lower ends and directed inwardly toward

the flanges 4, said guide flanges 8 preventing any twisting movement of the locking ring on the stretching members 3 when being slid thereover or during the clamping of 5 a tie to the stretching members.

Arranged between the opposing faces of the stretching members 3 is the coiled spring 10, which coiled spring has one end connected to one member 3 as at 11 and its opposite end connected to the inner face of the other stretching member as at 12, thus normally urging the members away from one another.

The necktie designated A has its smaller 15 medial portion arranged over the looped portion 2 thus positioning the ends on the opposite sides of the stretching members and upon the plane surfaces thereof, the ends are extended beyond the enlarged ends of 20 the stretching members as shown at 13 in Fig. 2 of the drawings, the locking ring 5' is then slid over the smaller ends of the stretching members and urged toward the larger ends thereof, thus firmly clamping 25 the necktie against the plane V-shaped surfaces of the stretching members 3.

A wire supporting hook 14 is substantially U-shaped and has its legs bent angularly as at 15 and arranged under the loop portion 30 2 of the stretching members, thus firmly positioning the supporting member 14 in position, and the web or bight portion of the U-shaped member 14 is constricted as at 16 to provide a support which is adapted to be 35 arranged upon a nail, hook or the like for supporting the stretcher when assembled in position upon a support or the like.

When the locking ring 5' is arranged upon the necktie and moved along toward the 40 larger ends of the stretching members 3, it can be readily seen that the creases of the tie are removed when the tie is firmly clasped upon the plane surfaces of the stretching members 3 and kept in a stretched position 45 until wanted for use. When it is desired to remove the tie all that is necessary is to

force the locking ring 5' toward the smaller ends and remove the same entirely therefrom, thus releasing the tie so that the same may be taken from the stretcher and used. 50

What is claimed is:

1. A necktie stretcher comprising a flat body bent at its medial portion to provide spaced substantially V-shaped stretching members, a supporting loop arranged at the 55 medial portions of the members, longitudinally extending guide flanges formed integrally with the inner face of one of said stretching members, a coiled spring arranged between the opposing faces of the members 60 adjacent their enlarged ends for normally urging the members away from one another, and a locking ring slidably arranged over the members, and means carried by the locking ring to prevent the twisting of the locking ring upon the members. 65

2. A necktie stretcher comprising a flat resilient body looped at its medial portion to provide stretching members having substantially V-shaped plane surfaces, a pair of 70 spaced longitudinal guide flanges formed integrally with one of said members adjacent the opposite side longitudinal edges thereof, a spring arranged between the opposing faces of said members adjacent the 75 enlarged ends thereof, and a supporting loop at the medial portions of said members, a locking ring slidably arranged on said members, and guide flanges formed integrally with the side walls of the locking ring 80 against the under side of one of said stretching members for preventing any twisting movement of the locking ring upon the stretching members, as and for the purpose specified. 85

In testimony whereof I affix my signature in presence of two witnesses.

GUY A. MAHANEY.
